CLOTH CLAMP

Filed June 18, 1932

UNITED STATES PATENT OFFICE

HARRY W. BUTTERWORTH, JR., OF PHILADELPHIA, PENNSYLVANIA, ASSIGNOR TO
H. W. BUTTERWORTH & SONS COMPANY, A CORPORATION OF PENNSYLVANIA

CLOTH CLAMP

Application filed June 18, 1932. Serial No. 617,937.

The object of my invention is to provide a cloth clamp, for textile machinery such as tenters, etc., in which the fixed jaw has its gripping surface covered by a pressed sheet metal plate which may be definitely fitted in position without the use of rivets and without change of its shape under the clamping stress impressed upon the plate when being frictionally positioned upon the chain link or body portion.

Heretofore, the cast metal body portion of the cloth clamp has been machined in such a manner as to present a flat upwardly directed surface which supports the pressed sheet metal plate which constitutes the gripping surface, said plate being riveted in position or otherwise shaped to frictionally grip the forward edge of the body whereby it is held against becoming shifted or loose upon the body. It has been found, however, very difficult to so shape the sheet metal plate that it will adapt itself accurately to the machined body portion of the clamp so that the said sheet metal portion may be forced into position to properly co-act with the movable gripping jaw and, at the same time, to insure sufficient friction to prevent the plates from becoming shifted or loosened, the result of which would cause imperfect gripping and failure to retain its grip upon the fabric.

By my present improvements, I provide the plate with a grooved or recessed portion which permits a close fit to the flanged edge of the body part whereby the plate will position itself accurately upon the body without being distorted in any manner as would impair the close fitting, and with a minimum amount of stress between the two parts. In addition to this accurate fitting of the plate upon the body as to retain a perfect operative relation, I provide preferably at the middle portion of the plate a weakened portion which may be readily bent inward and be received within a slotted portion of the body, whereby the plate is held against longitudinal shifting upon the body and without being subjected to any bending or distortion which might cause the plate to be loosened upon the body of the clamp.

In adapting my improvements to a cloth clamp for textile machinery, I first shape the body portion of the cloth clamp to provide a perfectly flat upper surface and a suitably shaped longitudinal edge which provides an under rib or bead portion, and with said body I combine a flat plate which fits accurately to the surface of the machined clamp, said plate also provided at its forward edge with a groove or socket shaped accurately to closely receive and grip the flanged edge of the body, it being understood that the plate engages one end of the flange of the body and is forced longitudinally thereof to its final position. I further provide the plate with two closely positioned saw cuts for the purpose of providing a short length of the flange which may be bent inward as a tongue part fitting within a notch-like portion of the flange of the body part to hold the plate against longitudinal movement on the body.

With these and other objects in view, the nature of which will be more fully understood from the following specification, the invention consists in the novel features of construction hereinafter more fully described and defined in the claims.

My improvements will be better understood by reference to the drawing, in which: Fig. 1 is a side elevation of a cloth clamp for textile machinery embodying my invention; Fig. 2 is a front view of the same; Fig. 3 is a vertical section taken on line 3—3 of Fig. 2; Fig. 3a is a sectional view taken on line 3a—3a of Fig. 3; Fig. 4 is an inverted perspective view of a portion of the plate removed from the cloth clamp; Fig. 5 is a perspective view of the flanged edge of the table portion, looking upward and adapted to receive the plate shown in Fig. 4; Fig. 6 is a transverse section corresponding to Fig. 3, but of a modification thereof; Fig. 7 is a modification of the structure shown in Fig. 5; and Fig. 8 is an inverted perspective view of the modified form of plate shown in Fig. 6.

3 is the body of the cloth clamp and may be provided with the usual extensions and shapes to provide a link structure 2 as an in-

tegral part of the body. This body part has an overhanging arm 5 to which the pivoted jaw 6 is hinged at 7 and is provided with an operating arm 8 by which it may be positively tilted in the act of releasing the goods or during a time when it is being manipulated for gripping the fabric. The gripping end of the pivoted jaw 6 is preferably provided with a steel gripping portion 9. The body part 3 may be extended forward in a table portion 4 and its extreme forward edge 12 may be shaped as at 12a to receive a grooved clamping portion 14 on its underside.

10 15 10 is the plate which fits flat upon the table portion 4 and has its forward part bent or pressed into a groove-like channel as at 11 and 14. When the plate 10 is fitted to the flange portions 12 and 12a and moved 20 longitudinally, it grips the flange portions 12 and 12a of the body without in any way distorting the plate in its close relation to the table part 4 and 12. To insure its not being capable of further longitudinal shifting, the plate in Figs. 4 and 8 is provided with two transverse saw cuts to form between them a tongue portion 14a. This tongue portion fits into a recess formed in the flange portion 12 between the points 15, 25 15, in Figs. 2, 3 and 3a, and 5, and is bent inward to fit in the said recess so as to constitute a lock to prevent longitudinal shifting of the plate upon the body part 4—12.

30 35 As the part 10 is quite extensive, it is desirable that its rear end 10a shall be held against riding upward and this is accomplished by causing said edge 10a to be arranged to fit under the overhanging edges 13 and it assumes this position at the time 40 that the plate 10 is slid longitudinally upon the flanged edge 12a of the part 12.

45 While I have preferred that the flanged edge of the table portion 4 shall be formed by the angular surfaces shown in Figs. 1, 3 and 5, with a corresponding angularly bent grooved plate shown in Figs. 1, 3 and 4, and fitted thereto, these parts may be slightly modified as indicated in Figs. 6, 7 and 8, wherein instead of the flat angular portion 50 12a of the double edge a downwardly extending body portion 12ax shown in Figs. 6 and 7 is employed and adapted to cooperate with the plate structure shown in Figs. 6 and 8. In this latter construction, the plate 10 shown 55 in Fig. 8 is substantially the same as the plate structure shown in Figs. 1, 3 and 4, and is provided with a tongue portion 14a adapted to fit down into a groove formed between the points 15, 15, to retain the plate 60 from being shifted longitudinally.

65 As it is most important in tentering or other machines in which the gripping jaws are required to grip delicate fabrics without injury thereto it is necessary that provision shall be made for a perfect working

alignement between the gripping edge of the pivoted jaw and the upper surface of the plate 10 of the fixed jaw. This is accomplished by giving to the lower edge 9 of the pivoted jaw a straight alignement parallel to its axis 7 of the pivoted gripping jaw and also adapted to lie in the same plane with the gripping edge of the part 9, so that every portion of the parts 10a and 9 insure perfect and uniform gripping cooperation. This 75 enables a firm hold on the fabric with a minimum amount of compression due to the gripping action of the parts.

80 A trigger mechanism is shown for automatically putting the pivoted gripping jaw 6 into gripping relation to the fixed jaw by providing a loose pawl 16 hinged at 17 to the rear portion of the body part and normally held in raised position by the cloth. The pawl 16 is provided with a slot 18 in which a transverse pin 20 is received, said pin being secured to the rear end of a projecting arm 19 extending from the pivoted gripping jaw 6.

85 It will be understood that if there was a cloth layer between the gripping edge 9 and the under part of the pawl 16 and the latter resting upon the textile fabric (not shown), the gripping edge 9 of the pivoted jaw would be slightly above the fixed gripping surface 10. It will also be understood that as the cloth would be moved to the right, the pawl will ultimately be released 90 when the selvage of the fabric is moved so as to be close to the movable jaw 6 of the clamp, but which when slipped from under the pawl permits it to drop into gripping relation as shown, and when it would be holding the cloth close to its selvage. Nearly all cloth clamps are provided with trip mechanisms of one kind or another and, therefore, I do not restrict myself to any particular tripping mechanism.

95 It will now be apparent that I have devised a novel and useful construction which embodies the features of advantage enumerated as desirable, and while I have in the present instance shown and described the preferred embodiment thereof which has been found in practice to give satisfactory 110 and reliable results, it is to be understood that I do not restrict myself to the details stated as the same are susceptible of modification in various particulars, without departing from the spirit or scope of the invention.

115 I claim:

120 1. A cloth clamp for textile machinery, comprising a link-shaped body having a table portion and interlocking flange there-of, combined with a pressed metal plate having a flat clamping surface and resting upon the table portion so as to constitute the fixed jaw of the clamp, said plate having a groove-shaped flange portion of a size and form 125

to longitudinally slide upon the interlocking flange of the table portion to closely and accurately fit over the flange, said plate also having a narrow tongue pressed inward into a recess formed across the under side of the flange portion to lock the plate against longitudinal movement thereon, and a loosely hinged clamping jaw having a longitudinal clamping edge for clamping the fabric between it and the plate surface.

2. The invention of claim 1, wherein further, the rear edge of the pressed metal plate is fitted in an under-cut part of the body portion.

15 3. The invention according to claim 1, wherein further, the interlocking flange is provided on its underside with an inclined face and groove therein, and wherein also the groove-shaped flange portion is dove-tail shaped in cross section to correspond to and receive the interlocking flange of the table portion.

25 4. A cloth clamp for textile machinery, comprising in combination, a body portion having a pressed metal flanged plate formed with a clamping surface and a longitudinal groove, said grooved flange slidably engaging the body portion to accurately fit thereupon and said plate locked upon the body portion by means of a narrow tongue extension of the flange pressed inward to tightly fit into a recess in the under-surface of the body portion to hold the plate against longitudinal movement thereon, and a loosely hinged clamping jaw having a longitudinal clamping edge for clamping the fabric between it and the plate surface.

30 5. The invention according to claim 4, wherein further, the flat clamping surface of the pressed metal body is re-surfaced parallel to the axis of the loosely hinged clamping jaw and the clamping edge thereof whereby the gripping action upon the cloth is uniform throughout the length of the

35 45 clamping jaw.

In testimony of which invention, I hereunto set my hand.

HARRY W. BUTTERWORTH, JR.
